CLOTHES HAMPER

Harold D. Hulterstrum, Baraboo, and Jack Collins, Milwaukee, Wis., assignors to Flambeau Plastics Corporation, Baraboo, Wis., a corporation

Application August 1, 1957, Serial No. 47,192

Term of patent 14 years

(Cl. D58—4)

Fig. 1

Figure 1 is a perspective view of a clothes hamper, showing our new design, looking toward the front; and Figure 2 is a perspective view of the hamper looking from the rear.

The characteristic features of our design for the clothes hamper disclosed reside in the continuous upper portions having four walls gradually inclined upwardly as shown.

We claim:

The ornamental design for a clothes hamper, as shown and described.
